(57) **CLAIM**

I claim the ornamental design for a robotic lawnmower, as shown and described.

DESCRIPTION

FIG. 1 is an isometric view of the robotic lawnmower showing my new design;

FIG. 2 is a front view of the robotic lawnmower shown in FIG. 1;

FIG. 3 is a rear view of the robotic lawnmower shown in FIG. 1;

FIG. 4 is a left side view of the robotic lawnmower shown in FIG. 1;

FIG. 5 is a right side view of the robotic lawnmower shown in FIG. 1;

FIG. 6 is a top view of the robotic lawnmower shown in FIG. 1;

FIG. 7 is a bottom view of the robotic lawnmower shown in FIG. 1; and,

FIG. 8 is another isometric view of the robotic lawnmower of FIG. 1.
